UNITED STATES PATENT OFFICE.

CHARLES YINGLING, OF METUCHEN, NEW JERSEY.

GRATE.

SPECIFICATION forming part of Letters Patent No. 671,905, dated April 9, 1901.

Application filed October 4, 1898. Serial No. 692,594. (No model.)

To all whom it may concern:

Be it known that I, CHARLES YINGLING, a citizen of the United States, residing at Metuchen, in the county of Middlesex and State of New Jersey, have invented a certain new and useful Improvement in Grates, of which the following is a specification.

This grate may be used with furnaces for any purpose, but is intended more especially for grates used in connection with steam-boiler furnaces, and I will describe it as so applied. It is of the class known as "double-shaking," having provisions, including one vibrating lever, for rocking the alternate sections in opposite directions. I employ such a form and arrangement of the sections that the fingers can never be overheated. The fire is never allowed to get below the ends of the fingers, and the metal of the fingers, while exposed to high temperature on their upper surfaces, is always cooled by a flow of air upward.

The accompanying drawings form a part of this specification and represent what I consider the best means of carrying out the invention.

Figure 1 is a plan view with certain portions at the back of the grate omitted. Fig. 2 is a partial elevation and a longitudinal vertical section on the line 2 2 in Fig. 1, showing the several sections of the grate at rest for supporting the burning fuel. Fig. 3 is a corresponding elevation showing the several sections in the act of being rocked. Fig. 4 is an elevation of one of the removable end pieces viewed from the right in Fig. 1, and Fig. 5 is a corresponding end elevation. Figs. 6, 7, 8, and 9 are on a larger scale. Fig. 6 is a vertical cross-section of a portion in and adjacent to one of the side bars of the frame with some of the adjacent parts in elevation. Fig. 7 is a corresponding cross-section at another point in and near the middle bar. Fig. 8 is a perspective view of one of the rocking portions or sections detached. Fig. 9 is a longitudinal vertical section of a portion of an elevation of one of the detachable but otherwise fixed portions of the structure.

Similar letters of reference indicate corresponding parts in all the figures where they appear.

A A are the side frames; A' A', the cross-frames at the ends of the grate; A², a sepa-

rately-formed longitudinal piece traversing the mid-width, and A³ A³, &c., the separately-formed legs rigidly connected by bolts and nuts securing the latter to the other portions of the framing. These parts, rigidly united, constitute the framing which supports the grate-sections and which by the aid of brackets A⁴ and center-pins A⁵, bolted on the boiler-front, carry the operating-levers.

On the inner face of each of the side frames A A are pockets a', which support the ends of two series of movable bearers or rocking shafts B and C, Fig. 2, which are each supplied with a series of parallel fingers B' C', respectively, presenting each a straight bearing-surface to support the burning fuel at a much higher level than the shaft. These parts are cast integral, and in the connecting metal between the fingers and the shaft is a large hole b, which allows the circulation of air transversely through the part and reduces the conduction of heat downward. Each rocking section B has also an arm B², extending downward and carrying a short transverse pin B³. These sections are so formed and applied together that the fingers of each section lie between the ends of the fingers of the adjacent section. They are matched with looseness to allow proper uniform air-spaces. The spaces may vary according to the size of the coal to be used.

I provide two longitudinal link-bars D and E, connected to the several pins B³ C³, the bar D being connected to the pins B³ of one series of sections of the grate and by its longitudinal movement causing them all to rock simultaneously in the same direction and the bar E being similarly connected to the pins C³ on the arms C², carrying the fingers C', the shafts C and these several attachments being interposed between the several sections B and similarly supported in pockets in the framing and rocking always in the opposite direction to the motion of the other series B. Each of these horizontal links D and E has a rigid arm extended downward, marked, respectively, D' E'.

G is a hand-lever turning on the pin or pivot A⁵ and having pins G' G² set therein above and below the center A⁵, which serve as pivots for links I J, which are extended through holes a² a³ in the adjacent frame A' and are

provided with screw-threaded portions which are engaged loosely each in a hole in the corresponding pendent arm D' or E' and are allowed to work the rods, and therefore the connected grate-sections, by the aid of adjustable nuts K and adjustable opposing nuts K'. One link, I, is thus loosely and adjustably connected to the bar D and the other, J, to the bar E. When the lever G is vibrated by the attendant, the bars D and E are moved simultaneously endwise, causing the sections B and C to rock correspondingly in opposite directions and also to carry their upper surfaces forward and backward relatively to each other. The ends of the fingers remain always more or less locked or interleaved, not only when the grate-sections are at rest, with their bearing edges B' C' level, but also when they are rocked into extreme forward and rearward and extreme inclined position and in all the intermediate positions. There is no chance for the burning fuel to surround and "burn" the ends of any of the fingers. It can only lie on the top, and there is always free access for air to flow up past the metal below and convey upward the heat.

The considerable depth of each shaft B and C below its fuel-supporting surface B' C' and the thinness of the metal connections prevent any rapid transmission of heat downward. The rocking shafts are kept cool by the flow of cool air upward from below. The upper edge of each side frame A is cast with deep undercut notches *a*, extending down something like half the depth of the bar, dividing the upper portion of the latter into short lengths, which when heated by the glowing coals thereon may expand and contract independently without bending or straining the main body A. The notches *a* are increased in width at the bottom, so that there is little metal to conduct the heat downward from the separated portions A~~2~~ at the upper edge. These upper portions A~~2~~ may assume any temperature required short of melting, and each will expand and contract independently without straining the supporting portion of the frame below.

In the mounting of new sections B or C in my frame or when at any time it shall be judged expedient to adjust the mounting afterward it is easily accomplished by adjusting the nuts K and K'.

Besides the two series of rocking sections B and C, I provide two loose sections or bars A⁶, one at each end of the frame, which are not capable of rocking; but each extends a series of fingers A⁸ in a uniformly-level plane to lie between the contiguous finger ends of the adjacent rocking sections.

The cross-pieces of the fixed framing have each an offset *a*⁴ at about the mid-height on the inner face. These receive and support the removable bars A⁶, the stationary fingers of which extend inward at the mean level of the tops B' C' of the rocking sections. These removable bars are kept in place partly by

stout internal ridges A⁷, one near each end of each end frame A'. These bars A⁶ are shown in two lengths, the inner end of each being held up by an offset *a*⁵ in the middle-bar A². This middle bar is itself removable, each end being supported in a suitable socket formed at the mid-length of each cross-bar A' on the inner face. The plan view, Fig. 1, omits one line of fingers to show more clearly the inner ends of the removable bars. These said removable bars A⁶ are peculiarly formed by having between each of the fingers A⁸ and the next an undercut notch corresponding to the notches *a* in the side frame—that is to say, a space extending down about half the depth of the bar, open, but narrow, at the top and wider below. This construction affords the requisite strength for supporting the fingers A⁸ and limiting the conduction of heat from the top downward and allows ample space at short intervals for the greater expansion of the upper edge under the greater heat to which it is subjected. These bars A⁶ being in separate lengths cannot warp injuriously from the effects of heat.

It will be noted that each grate-bar, including its shaft and fingers, is in two sections, so that the entire rocking grate-bars are presented in two longitudinal series. This permits the convenient shaking of but one-half of the grate, distinct link and operating-lever devices being provided for each section. Fig. 7 illustrates the divided character of a grate-bar and how it bears at its divided portion on the central longitudinal bar A².

I attach importance to the fact that the perforations *b* in the fingers C' are in line with each other and with the spaces between the inverted triangles when the grate is in condition for use, because it allows a direct and active movement of the air therethrough, tending by the connection due to the cold air, as well as by the large surface presented for radiation, to promote the durability of the grate.

Modifications may be made without departing from the principle or sacrificing the advantages of the invention. There may be a greater or less number of the sections B and C. The distance of the pivots G' G² from the center A⁵, on which the lever G turns, may be varied, so that a given amount of rocking motion of the lever G will give a greater or less turning motion to the several sections of the grate. The dimensions otherwise may be varied. I prefer to have the several fingers B' C' about six inches in length and to have the center of the rocking motion about three inches below the upper surfaces of the several sections and spaced about one and five-eighths inches from center to center and to have the fingers about one-half inch wide. Where nut or larger coal is to be used, wider spacing could be allowed. Parts of the invention can be used without the whole. The middle bar A² may be omitted. There may be more than one of the middle bars A², and

a corresponding shortening and increase in the number of the removable end pieces A⁶. The end pieces may be thus divided without increasing the number of the bars A² by providing a sufficient number of supports corresponding to the internal ridges A⁷, distributed along on the offsets a⁵ on the permanent pieces A'.

I have in my experiments made a large grate with as many as six of the removable pieces A⁶, of equal length, stretching along on a single permanent end piece of the grate.

I claim as my invention—

1. In a shaking-grate, the combination with a supporting-frame having a series of separated upright projections, of a series of fingers mounted on rocking shafts and perforated on a line with the spaces between the upright projections, and provisions for rocking the shafts, substantially as set forth.

2. In a shaking-grate, a supporting-frame having a series of upright projections, rocking shafts carrying a series of interleaved fingers perforated on a line with the spaces between the upright projections, connections with alternate shafts, separate connections with the intermediate shafts, and provisions for operating said connections so as to oppositely rock the two series of shafts all substantially as herein specified.

3. In a shaking-grate, the combination with a supporting-frame having a series of separated upright projections, of a series of interleaved fingers mounted on low-centered shafts and perforated contiguous to the same and on a line with the spaces between the upright projections, a horizontal link connected with arms extending down from alternate shafts another horizontal link connected with the arms of the intermediate shafts, a lever adapted to be rocked by the attendant, and connections from said links one above and one below the center of motion of such lever and thereby oppositely rocking the two series of shafts, all substantially as herein specified.

4. In a shaking-grate, the combination with a supporting-frame having a series of separated upright projections, of a series of interleaved fingers mounted on low-centered shafts and perforated contiguous to the same and on a line with the spaces between the upright projections, a horizontal link connected with arms extending down from alter-

nate shafts, another horizontal link connected with the arms of the intermediate shafts, a lever adapted to be rocked by the attendant, rigid arms D', E', depending from the links, rods I, J, having threaded inner ends adjustably connected by nuts K K', with said depending arms, and at their outer ends one above and one below the center of motion of the operating-lever, whereby the rocking of the latter will oppositely rock the two series of shafts, all substantially as herein specified. 65

5. In a shaking-grate, the combination with the frame having a series of upright projections and the lower side bearings and engaging means at its corners, and the shafts resting in said bearings and having fingers perforated on a line with the spaces between the stationary upright projections of the frame, of a central longitudinal brace-bar detachably resting in pockets therefor in the end of the frame, removable grate-sections retained by the corner-ridges and central brace-bar, and provisions for rocking the shafts in their bearings, substantially as herein specified. 75

6. A fire-grate characterized by a side bar of the supporting-frame of which bar the upper edge is composed of separated upright projections in the form of inverted triangles attached at their apexes and placed parallel with the body of said bar, in combination with grate-bars having a series of fingers horizontally perforated, the perforations being on a line with the spaces between the upright projections of the side bar substantially as described. 85

7. A fire-grate characterized by a removable middle bar A² having its upper edge composed of upright inverted triangular projections formed integral and fixed side bars A having similar projections coinciding therewith, and having rocking grate-sections occupying the main area of the grate between such bars, said rocking sections having apertures b which when the grate is in use are in line with the spaces between said triangular inverted projections all adapted to serve substantially as herein specified. 95 100

In testimony that I claim the invention above set forth I affix my signature in presence of two witnesses.

CHARLES YINGLING.
